CLAIM

The ornamental design for a chair, as shown and described.

DESCRIPTION

FIG. 1 is a front elevational view of the chair comprising my new design;

FIG. 2 is a right side elevational view thereof, the opposite side elevational view being a mirror image thereof; and, FIG. 3 is a top plan view thereof.

The broken lines showing a seat cushion and the central portion of the backrest are for environmental purposes only and form no part of the claimed design.

1 Claim, 1 Drawing Sheet

FIG. 2

FIG. 3

FIG. 1
